US0D1065914S

(12) **United States Design Patent** (10) **Patent No.:** **US D1,065,914 S**
(45) **Date of Patent:** **** Mar. 11, 2025**

(54) **ELECTRIC GRINDER**

(71) Applicant: **Zhuhai Kelitong Electronic Co., Ltd,**
Guangdong (CN)

(72) Inventor: **Xiaoxian Song**, Guangdong (CN)

(73) Assignee: **Zhuhai Kelitong Electronic Co., Ltd,**
Zhuhai (CN)

(**) Term: **15 Years**

(21) Appl. No.: **29/845,124**

(22) Filed: **Jul. 5, 2022**

(30) **Foreign Application Priority Data**

Feb. 15, 2022 (CN) 202230072938.X

(57) **CLAIM**

The ornamental design for an electric grinder, as shown and described.

DESCRIPTION

FIG. 1 is a top and front side perspective view of an electric grinder, showing my new design;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken lines in the figures illustrate portions of the article which form no part of the claimed design.

1 Claim, 7 Drawing Sheets
